ROTOR FOR RADIAL TURBINES

Alfred Büchi, Winterthur, Switzerland

Continuation of application Serial No. 616,203,
 September 14, 1945, which is a division of applica-
 tion Serial No. 462,859, October 21, 1942.
 This application August 15, 1949, Serial No.
 110,448. In Canada August 18, 1942

8 Claims. (Cl. 253—117)

1

This invention is a continuation of my application Serial No. 616,203 which itself was a division of my application Serial No. 462,859, now Patent No. 2,390,506, dated December 11, 1945, and relates to rotors for radial turbines particularly adapted for use with hot gaseous motive fluids consisting of a disc-like rotor body presenting a plurality of blades successively spaced from each other to form the side walls of a plurality of successive passages, the said body forming bottom walls for the said passages between adjacent blades, the passages being arranged to receive gas admitted substantially radially at the outer periphery of the rotor and to direct the gas inwardly toward the axis of the rotor, the bottom walls being curved from radial to axial directions as the gas flows radially inwardly and then axially from the inlet to the outlet ends of the passages, the inlet end of the bottom wall lying in a plane substantially perpendicular to the rotor axis and the outlet end of the bottom wall extending in a direction along the rotor axis, each blade extending obliquely to the rotor axis and each side of each blade lying substantially within a single plane.

In a further embodiment of my invention, the cross sectional area of the outlet end of each passage and the inclination of the outlet ends of the blades produce relative gas velocities adjacent the base and adjacent the tip of the outlet end of each blade which are substantially equal to each other and also produce absolute gas velocities adjacent those points which are substantially equal to each other. Through these measures reciprocal influences and disturbances of the gas flow in the passages of the turbine rotor and at the exit ends of the rotor blades are avoided. The turbine rotor blades at their exit ends are so directed that, at least behind the interior of the rotor, a substantially axial velocity results. The radially outer portions of the exit ends of the rotor blades may also have slightly bent surfaces. The angle relative to a plane perpendicular to the rotor axis at which the tip of the outlet end of each rotor blade is disposed may differ from the angle relative to said plane at which the base of the outlet end of the blade is disposed so that an absolute velocity is imparted to the gas adjacent the tip of the blade differing in direction from the absolute velocity of the gas adjacent the base of the blade thereby creating a vortex in the gas flow leaving the rotor. The blades could be initially plane, disposed obliquely to the turbine axis. The plane surfaces can then be bent at their exit ends. The outlet ends of the rotor blades

2

may be cut off obliquely to the turbine axis so that they lie substantially in a conical surface co-axial with the turbine axis. By this means the angle through which the flow of gas is diverted from its radial inlet to the outer, more axial exit direction of the turbine is reduced. In a radial turbine according to the invention the rotor may be combined with a diffusor through which the rotor discharges and which is adapted for effective conversion of velocity into pressure in the exit section of the gases, whereby the gases leaving the rotor are directed substantially axially through the diffusor.

Each rotor blade may lie mainly within a single plane extending from its entire inlet area to its lateral ends joining the disc-like body of the rotor or may have slightly bent surfaces toward the radially outer portions of the exit ends of the blades which bent surfaces produce a slightly tangentially directed velocity in the gases adjacent the surface of the diffusor creating a vortex in the gas flow in the diffusor. This measure is intended to obtain in the adjacent diffusor a conversion of velocity into pressure as favourably and uniformly as possible and in addition to minimize separation of gas flow from the wall surfaces. The minimum internal diameter of the diffusor at its inlet end may be smaller than the diameter across the tips of the turbine blades at their outlet ends and the minimum cross sectional area of the diffusor at its inlet end may approximate the aggregate cross sectional areas of the said passages at their outlet ends. The reason for this construction is to maintain as constant as possible the absolute velocity of the gas discharging from the turbine rotor at the inlet end of the diffusor for the purpose of avoiding energy losses due to vanishing of velocity resulting from the terminal thickness of the turbine blades.

Several embodiments of the invention inclusive of details thereof are illustrated, by way of example only, in the accompanying drawings, in which

45 Figs. 1 to 6 represent a single stage gas turbine, as a first embodiment of the invention, the turbine being in driving engagement with a blower rotor and having four different gas supply conduits,

50 Fig. 1 being a section on the line I—I in Fig. 2;
 Fig. 2 a section on the line II—II in Fig. 1;
 Fig. 3 a section on the line III—III in Fig. 2;
 Fig. 4 a perspective view of the turbine rotor inclusive of the blading thereof;
 55 Fig. 5 a view of a modified detail of Fig. 4, and

Fig. 6 a sectional view of a modified detail of Fig. 1.

Fig. 7 shows a side elevation partly in section on the line VII—VII in Fig. 8 of a second embodiment of the invention;

Fig. 8 is a sectional view on the line VIII—VIII in Fig. 7;

Fig. 9 is a sectional view of the line IX—IX in Fig. 8;

Fig. 10 shows a modification of a detail of Fig. 7;

Figs. 11 and 12 each represent diagrammatically various velocities; and

Fig. 13 is a section on the line XIII—XIII in Fig. 1.

Fig. 1 shows a radial turbine rotor 1 which is rotating in a bearing support 3 by means of a shaft 2. The numeral 4 designates the turbine admission casing whereas 5 refers to the nozzle carrier ring containing the inlet blades 6 and 15 (Figs. 2, 8 and 13) and 7 refers to a closure member which is provided with a cooling space 8 and is arranged between the gas inlet casing 4 and the compressor collecting casing 9.

The turbine rotor forms an integral piece having a disc-like wheel body 1 the flat blades of which are, for example, worked out of the material of this body. These blades 17, one of which is shown in elevation centrally of the wheel at 17, 18 (Fig. 1), have the characteristic feature that their surfaces project from the rotor disc 1 in oblique relation to the axis of the rotor and that they extend radially across the full blade width at least at the outer circumference of the rotor disc, when seen in the direction of the rotor axis. At the bases 18 of the blades 17, at the points where the latter are connected to the wheel disc 1, thickened blade portions are provided for reasons of strength. The bases of the blades, when seen transversely to the rotor axis, are curved towards the direction of this axis so as to divert the passages between the blades from the radial into the axial direction.

In thus hollowing out the turbine rotor 1 in the axial direction toward the exit end 20, for forming these passages between the blades 17, care is taken that relatively smooth, that is, gently curved contours 21 are formed. When a diffusor 22 is arranged behind the turbine rotor, as shown in the examples illustrated in Figs. 1, 6, 7 and 10, the direction of inclination of the rotor blades and the cross sections between the rotor blades are so designed that the gases leave the discharge edges 20 under a lower pressure than the discharge pressure at the end 23 of the diffusor 22, and at relatively higher velocity, and then enter the rectilinearly conically widening diffusor 22. The design of the diffusor 22 is such that at the end 23 thereof the pressure of the gases increases substantially to the value of the discharge pressure in the exhaust pipe or to atmospheric pressure, if exhausting into the atmosphere takes place.

In order to provide for the conversion of velocity taking place in the diffusor 22 to be efficient, a conically tapering guide piece 24 adjoining the hub of the turbine rotor 1 may be arranged in the interior of the diffusor 22. This guide piece 24 prevents the velocity of the gas discharging from the turbine rotor 1 from vanishing abruptly, at loss of energy on the inside of the blading 17 of the turbine rotor 1.

Instead of arranging the diffusor 22 coaxially with the turbine, it may be arranged to discharge in another direction, for example as shown at 22'

in Fig. 6. In such a case, the gases discharging from the turbine rotor blading 17 are supplied to the diffusor 22' through an intervening pipe bend 25 which also may be provided with a guide piece, such as 26, having the effect of preventing the velocity from being abruptly reduced.

In the center of Figs. 2 and 13 the construction of the turbine rotor blades 17 is shown in detail. Although the blades 17 forming the gas passages are generally flat and incline to the rotor axis, as mentioned above, the inlet end portions 19 of the blades 17 adjoining the outer periphery of the rotor extend in radial direction. The discharge end portions 20 of these blades 17 also extend radially or are only slightly inclined to the radial direction. The inlet casing 4 of the turbine is integral with the diffusor arrangement 22 (Fig. 1). Four supply conduits 10, 11, 12 and 13 (see also Fig. 3) form an arrangement of crowded convolutions so that the outer diameter of the casing 4 is reduced to a minimum. The areas of free passage of the spiral entrance portions of the conduits 10, 11, 12 and 13 decrease to such an extent that uniformity of velocity is maintained up to the entry of all the tapering nozzles 14 and but a relatively slight diversion of the gases into the direction of admission is required to take place. Between each pair of the spiral inlet conduits 10, 11, 12 and 13, one of four separating blades 15 (Figs. 2, 8 and 13) is provided, and in each interstice therebetween are arranged only two nozzle blades 6 which also extend in the tangential direction and which jointly ensure that the gases are admitted to the turbine rotor in the required direction and at the appropriate gas velocity. Due to the tangential guiding effect produced by the inlet conduits 10, 11, 12 and 13, that is, that of the separating blades 15 and the intervening blades 6, the flow of gas undergoes diverting movements at large radii of curvature throughout. Consequently the losses of energy suffered in advance of the turbine rotor are only small. Fig. 2 further shows plainly the manner in which the supply conduits 10, 11, 12 and 13 are crowded into narrow convolutions up to their exit ends. At 22 and 24 in Fig. 1, the outer wall and the inner guide wall respectively of the diffusor are shown in cross section.

Fig. 3 exemplifies the manner in which the four separate supply conduits 10, 11, 12 and 13 are relatively arranged on the gas entrance side.

Fig. 4 being a perspective view of the turbine rotor 1, clearly shows the radially directed entrance ends 19 and the approximately radially directed exit ends 20 of the turbine rotor blading 17. From this illustration it will be plainly seen that the approximately plane flanks of the rotor blades extend obliquely to the turbine axis, and that the thickness of these blades increases particularly in the radial direction and toward the blade bases 18 at the turbine wheel disc.

The second embodiment of the invention as shown in Fig. 7 comprises a gas turbine with only two inlet conduits 10' and 11'. The numeral 17' refers to the turbine rotor blades having inlet ends 19' and exit ends 20'. These exit ends 20' are cut off obliquely to the turbine axis (Fig. 7 sectional portion). It will be clearly seen that the innermost diameter of smallest length of the diffusor 22'' is smaller than the extreme diameter of the outer exit ends 20' of the turbine blades 17', commensurate with the obliquity of said ends. The reason for this construction is to obtain at the inlet end of the diffusor 22'' substantially the same absolute gas velocity as that existing at

the discharge end 20' of the turbine rotor 1, for the purpose of avoiding energy losses due to abrupt reduction of velocity. This is accomplished by keeping down the cross section of free passage at the inlet end of the diffusor 22', at least to such a size as to correspond with the effective absolute gas discharge area of the turbine rotor blading considering the terminal thickness of blades. In this construction the exit ends 20' of the blades lie in a conical surface coaxial with the turbine axis. By this means the angle through which the flow of gas must be diverted from its inlet area 19' up to the outer exit area 20' of the turbine rotor 1 is reduced, compared with an execution according to Fig. 1. The losses caused by deflection of the gas flow in the turbine blading are therefore decreased. When the velocity of the gas relative to the turbine blading is greater than its absolute velocity at the exit of the turbine blading, the deflection of the gas flow beyond, that is, outside of the turbine blading, where the gases enter the diffusor, causes less energy losses.

In a construction as shown in Fig. 7 no gap losses arise in the discharging gas at the point of transition from the turbine rotor 1 to the piece 24', in contrast to the construction shown in Fig. 1, due to the fact that no open gap extending transversely of the gas-stream exists between the turbine rotor and the diffusor.

In Fig. 8 as seen from the left hand side of Fig. 7, the form of the turbine rotor blades 17' inclusive of their radially directed inlet ends 19' and their substantially radially extending exit ends 20' is shown. The two supply conduits 10' and 11' forming a crowded arrangement of convolutions taper also in this case spirally toward the two blades 15 separating said conduits from each other. Within the interstices between said blades 15 only five nozzle blades 6 are arranged in the nozzle carrier ring 5 for each supply conduit, for leading the gases into the turbine rotor.

The conduits 10' and 11' are collaterally disposed with the joining line of their axes extending in parallelism with the turbine axis.

Fig. 10 represents a modification of the construction of the inlet nozzles 14 and a corresponding form of the turbine rotor blading 17''. The inlet direction of the nozzles 14 is no longer radial, but, when seen transversely to the turbine axis, inclined at an acute angle to the axis of the turbine rotor 1 which corresponds to the direction of flow of gas at point 16 in this figure. Now since the turbine blade entrances have the same obliquity as the nozzles, this arrangement results in a reduced angle of diversion of the flow of gas during the passage of the gas through the turbine rotor 1 from the radial direction as shown in Figs. 1 and 7 into the axial direction. The direction of the hollow parts or buckets of the turbine rotor blading 17'' must naturally then be in correspondence with the direction of gas admission, as shown in this figure.

Fig. 11 represents the gas inlet velocity triangle at the blade entrance 19 of the turbine, in which c_1 designates the absolute gas admission velocity, u_1 the velocity of the circumference of the rotor, and w_1 the relative gas admission velocity which is approximately radially directed in accordance with the present invention.

Fig. 12 represents the gas velocity diagrams at the exit end 20 of the turbine rotor. The character u_2' refers to the circumferential velocity at the extreme outer exit diameter, w_2' to the relative gas velocity thereat, and c_2' to the corre-

sponding absolute gas velocity. The character u_2'' represents the smaller circumferential velocity at the blade 18, w_2'' the relative gas velocity at the last named point, and c_2'' the corresponding absolute gas velocity.

According to the invention, the inclinations of the rotor blades and the dimensions of the cross sectional areas between these blades are so chosen that, as illustrated in Fig. 12, at the exit end of the turbine rotor the relative gas velocities w_2' and w_2'' are substantially equal to each other, and also the absolute velocities c_2' and c_2'' are substantially equal to each other. Further in the interior of the diffusor according to the invention a substantially axially directed velocity c_2'' must result, and at the outer diffusor circumference there may exist a slightly tangentially directed velocity c_2' producing a vortex in the gas flow. Both measures are intended to obtain in the diffusor 22 a conversion of velocity into pressure as favorable and uniform as possible and in addition little separation of gas from the wall surfaces even in a more widely flared and relatively shorter diffusor. For this purpose on the outer end the angle α_2' of the blades must be chosen to be smaller than at the inner end in accordance with α_2'' . For obtaining the corresponding exit angles α_2' and α_2'' (see Fig. 12 and the description thereof) in an arrangement according to the present invention, the blade surfaces can be formed firstly of initially plane surfaces in conformity with the exit angle α_2'' at the blade base 18, then the outer ends are bent up or pressed into the desired different direction in accordance with the exit angle α_2' , if required in hot state.

I claim,

1. A rotor for a radial turbine particularly adapted for use with hot gaseous motive fluids, consisting of a disc-like body presenting a plurality of blades successively spaced from each other to form the side walls of a plurality of successive passages, the said body forming bottom walls for the said passages between adjacent blades, the passages being arranged to receive gas admitted substantially radially at the outer periphery of the rotor and to direct the gas inwardly toward the axis of the rotor, the bottom walls being curved from radial to axial directions as the gas flows radially inwardly and then axially from the inlet to the outlet ends of the passages, the inlet end of the bottom wall lying in a plane substantially perpendicular to the rotor axis and the outlet end of the bottom wall extending in a direction along the rotor axis, each blade extending obliquely to the rotor axis and each side of each blade lying substantially within a single plane.

2. A rotor for a radial turbine as defined in claim 1 in which the cross-sectional area of the outlet end of each passage and the inclination of the outlet ends of the blades produce relative gas velocities adjacent the base and adjacent the tip of the outlet end of each blade which are substantially equal to each other and also produce absolute gas velocities adjacent those points which are substantially equal to each other.

3. A rotor for a radial turbine particularly adapted for use with hot gaseous motive fluids, consisting of a disc-like body presenting a plurality of blades successively spaced from each other to form the side walls of a plurality of successive passages, the said body forming bottom walls for the said passages between adjacent blades, the passages being arranged to receive gas admitted

substantially radially at the outer periphery of the rotor and to direct the gas inwardly toward the axis of the rotor, the bottom walls being curved from radial to axial directions as the gas flows radially inwardly and then axially from the inlet to the outlet ends of the passages, the inlet end of the bottom wall lying in a plane substantially perpendicular to the rotor axis and the outlet end of the bottom wall extending in a direction along the rotor axis, each blade extending obliquely to the rotor axis and each side of each blade lying mainly within a single plane extending from its entire inlet area to its lateral ends joining the disc-like body of the rotor and having slightly bent surfaces towards the radially outer portions of the exit ends of the blades.

4. The rotor as defined in claim 1 in which the angle, relative to a plane perpendicular to the rotor axis, at which the tip of the outlet end of each blade is disposed differs from the angle, relative to said plane, at which the base of the outlet end of the blade is disposed so that an absolute velocity is imparted to the gas adjacent the tip of the blade differing in direction from the absolute velocity of the gas adjacent the base of the blade, thereby creating a vortex in the gas flow leaving the rotor.

5. The rotor as defined in claim 1 in which the outlet ends of the blades are cut off obliquely to the turbine axis so that they lie substantially in a conical surface co-axial with the turbine axis.

6. In a turbine particularly adapted for use with hot gaseous motive fluids, the combination of a rotor and a diffusor through which the rotor discharges, adapted for effective conversion of velocity into pressure in the exit gases, the rotor consisting of a disc-like body presenting a plurality of blades successively spaced from each other to form the side walls of a plurality of successive passages, the said body forming bottom walls for the said passages between adjacent blades, the passages being arranged to receive gas admitted substantially radially at the outer periphery of the rotor and to direct the gas inwardly toward the axis of the rotor, the bottom walls being curved from radial to axial directions as the gas flows radially inwardly and then axially from the inlet to the outlet ends of the passages, the inlet end of the bottom wall lying in a plane substantially perpendicular to the rotor axis and the outlet end of the bottom wall extending in a direction along the rotor axis, each blade extending obliquely to the rotor axis and each side of each blade lying substantially within a single plane, whereby the gases leaving the rotor are directed substantially axially through the diffusor.

7. In a turbine particularly adapted for use with hot gaseous motive fluids, the combination of a rotor and a diffusor through which the rotor discharges, adapted for effective conversion of velocity into pressure in the exit gases, the rotor consisting of a disc-like body presenting a plurality of blades successively spaced from each other to form the side walls of a plurality of successive passages, the said body forming bottom walls

for the said passages between adjacent blades, the passages being arranged to receive gas admitted substantially radially at the outer periphery of the rotor and to direct the gas inwardly toward the axis of the rotor, the bottom walls being curved from radial to axial directions as the gas flows radially inwardly and then axially from the inlet to the outlet ends of the passages, the inlet end of the bottom wall lying in a plane substantially perpendicular to the rotor axis and the outlet end of the bottom wall extending in a direction along the rotor axis, each blade extending obliquely to the rotor axis and each side of each blade lying mainly within a single plane extending from its entire inlet area to its lateral ends joining the disc-like body of the rotor and having slightly bent surfaces towards the radially outer portions of the exit ends of the blades, which bent surfaces produce a slightly tangentially directed velocity in the gases adjacent the surface of the diffusor creating a vortex in the gas flow in the diffusor.

8. In a turbine particularly adapted for use with hot gaseous motive fluids, the combination of a rotor and a diffusor through which the rotor discharges, adapted for effective conversion of velocity into pressure in the exit gases, the rotor consisting of a disc-like body presenting a plurality of blades successively spaced from each other to form the side walls of a plurality of successive passages, the said body forming bottom walls for the said passages between adjacent blades, the passages being arranged to receive gas admitted substantially radially at the outer periphery of the rotor and to direct the gas inwardly toward the axis of the rotor, the bottom walls being curved from radial to axial directions as the gas flows radially inwardly and then axially from the inlet to the outlet ends of the passages, the inlet end of the bottom wall lying in a plane substantially perpendicular to the rotor axis and the outlet end of the bottom wall extending in a direction along the rotor axis, each blade extending obliquely to the rotor axis and each side of each blade lying substantially within a single plane, whereby the gases leaving the rotor are directed substantially axially through the diffusor, the minimum internal diameter of the diffusor at its inlet end being smaller than the diameter across the tips of the turbine blades at their outlet ends and the minimum cross sectional area of the diffusor at its inlet end approximating the aggregate cross sectional areas of the said passages at their outlet ends.
